UNITED STATES PATENT OFFICE.

HENRY H. BROWN, OF WASHINGTON COURT-HOUSE, OHIO, ASSIGNOR TO THE WONDER MANUFACTURING COMPANY, OF WASHINGTON COURT-HOUSE, OHIO, A CORPORATION OF OHIO.

STOVE.

SPECIFICATION forming part of Letters Patent No. 755,105, dated March 22, 1904.

Application filed May 22, 1903. Serial No. 158,218. (No model.)

To all whom it may concern:

Be it known that I, HENRY H. BROWN, a citizen of the United States, residing at Washington Court-House, in the county of Fayette and State of Ohio, have invented certain new and useful Improvements in Stoves, of which the following is a specification.

My invention relates to gas-stoves.

The object of my invention is to provide a simple and efficient construction consisting of few parts that can be easily and economically made and assembled, the arrangement being such as to afford perfect combustion and a maximum of radiating-surface, with means to limit the escape of heat through the chimney and reduce this loss to a minimum.

My invention consists of the constructions and combinations hereinafter described, and set forth in the claims.

In the accompanying drawings, which form a part of this specification, Figure 1 is a sectional view of a gas-stove embodying my invention. Fig. 2 is a plan of the base with the burner partly broken away to show inlet to the burner-conduit. Fig. 3 is a sectional view of same, showing the burner above its normal position. Fig. 4 is a detail showing the burner bolted in position; and Fig. 5 is a plan of the stove, taken from above the upper baffle-plate.

Like parts are represented by similar letters of reference in the several views.

The base of the stove I have shown consists of radial arms a , with rings a' , a'' , a''' , and a'''' thereon. The ring a' has supporting-legs a^5 , and the ring a'' is of suitable width for a groove or channel a^6 in its upper surface, having an inlet a^7 from a gas-conduit a^8 , to the screw-threaded outer end of which the gas connection is made.

The several parts may be made separately and secured together; but I preferably form the same in a single casting and have so arranged the parts that this can be done, thus giving an economical construction.

An upwardly-extending projection a^9 forms a groove in which the lower end of the outer shell a^{10} of the stove rests in contact with the

ring a' , and the inner and outer walls of the fire-chamber rest on the radial arms a , the inner wall a^{11} in contact with the ring a' and the outer wall a^{12} in contact with the ring a'' , the arrangement of the rings being such as to stay the walls in position. A burner consisting of a ring portion a^{13} , with a plurality of perforated upwardly-extending and preferably cone-shaped lugs a^{14} , is provided with a groove on its under side, adapted to fit over the groove in the ring a'' and form a conduit, through which the gas passes to the perforated lugs. The burner is secured to the base by bolts a^{15} .

In constructing the top of the stove I have provided a cover b for the fire-chamber and a ring portion b' , resting on the outer shell, to support the top cover b^2 of the stove. The parts b and b' I connect by arms b^3 , and I preferably cast said parts in one piece. The ring portion b' is provided with a suitable flange to rest on the upper edge of the outer shell of the stove and also engage the outer surface of said shell. The cover b is provided with downwardly-projecting flanges to contact and stay the walls a^{11} and a^{12} in position. Bolts b^4 , extending through the arms a of the base and the arms b^3 of the top, securely bind the stove together. A pipe b^5 leads from the fire-chamber to the chimney.

For the purpose of reducing the escape of heat into the chimney to a minimum, and thereby increase the heating capacity of the stove, I provide one or more partitions or baffle-plates b^6 in the fire-chamber, having perforations b^7 therein. Three such plates are preferably used, the perforations in the several plates varying in number and position to change the current from one side to the other of the fire-chamber. The position and number of these perforations is best shown in Fig. 5, two of the perforations being in the upper plate on the side of the stove opposite to the escape-pipe b^8 . There are three perforations in the next or middle plate, and these are represented by dot-and-dash lines in said figure. In the lowest plate there are five perforations represented by dotted lines. Re-

referring to the arrows in Fig. 1, it will be seen the current is guided from one side of the fire-box to the other until it escapes into the stack, and the perforations are reduced in number from five in the lower plate to two in the upper plate.

It will be seen I have provided a construction such that the top and base may each be cast in one piece, the latter including the lower half of the burner, so the stove can be easily and quickly assembled and secured together by bolts running from top to base. The central air-shaft and air-space about the fire-chamber gives a maximum of radiation, and the partitions or baffle-plates prevent loss of heat into the chimney. An opening b^s in the gas-conduit admits air to said conduit, and it will also be seen that the burner is so placed that there is an opening on each side thereof through the base, which, together with the separate upwardly-projecting perforated lugs, affords an ample supply of air to each burner to give perfect combustion. Perforations b^o in the shell give access to the fire-chamber to light the gas.

The heat-currents in the fire-chamber and the air-currents in the air-passages are shown by arrows in Fig. 1.

Having thus described my invention, I claim—

1. In a stove such as described, the combination with the side walls of the fire-chamber, of a series of partitions in said chamber between the burners and outlet for said chamber, having perforations therein, each succeeding partition from said burners having a less number of said perforations so disposed as to guide the heat-currents from one side to the other of said chamber, substantially as specified.

2. In a stove such as described, a base consisting of radial arms with a plurality of rings thereon leaving openings on each side thereof, one of said rings having a channel formed on the upper surface thereof and a casing forming a conduit opening into said channel, all cast integrally, substantially as specified.

3. In a stove such as described, a base consisting of radial arms with a plurality of rings thereon leaving openings on each side thereof, one of said rings having a channel formed therein and a casing forming a conduit opening into said channel, all cast integrally, said

channeled ring forming one portion of a burner, another channeled ring forming the other portion having a plurality of perforations therein, and means to secure said portions together, substantially as specified.

4. In a stove such as described, a base consisting of radial arms with a plurality of rings thereon leaving openings on each side thereof, supporting-legs, one of said rings having a channel formed on the upper surface thereof and a casing forming a conduit opening into said channel, all cast integrally, said channeled ring forming one portion of a burner, another channeled ring forming the other portion and having a plurality of upwardly-extending projections with perforations extending into said channel, and means to secure said portions together, substantially as specified.

5. In a stove such as described, the combination with three shells forming side walls of a fire-chamber, a central air-shaft and an air-space about the outer walls of said chamber, a series of partitions in said chamber having perforations therein, each succeeding partition from the lowest having a less number of said perforations so disposed as to guide the heat-currents from one side to the other of said chamber, of a base consisting of radial arms with a plurality of rings thereon leaving open spaces on each side thereof, one of said rings having a channel formed on the upper side thereof, and a casing forming a conduit opening into said channel cast integrally, said channeled ring forming one portion of a burner, another channeled ring forming the other portion and having a plurality of upwardly-extending cone-shaped projections with perforations extending into said channel, and means to secure said portions together, a top consisting of a circular portion having a central opening therein, a ring outside of said portion and arms connecting said portion and ring, said portion and ring having laterally, projecting flanges, all cast integrally, and means extending from said top to said base to bind and secure the parts together, substantially as specified.

In testimony whereof I have hereunto set my hand this 19th day of May, A. D. 1903.

HENRY H. BROWN.
